MATCHBOX CHESSMAN

Guglielmo Frascolla, New York, N. Y.

Application October 5, 1956, Serial No. 43,240

Term of patent 14 years

(Cl. D48—29)

Fig. 1 is a view in perspective of a matchbox chessman taken from above; and from the front.

Fig. 2 is a view in perspective taken from below and from the rear.

I claim:

The ornamental design for a matchbox chessman, substantially as shown.
